Primary Examiner — Lauren R Calve(74) *Attorney, Agent, or Firm* — Banner & Witcoff, Ltd.(57) **CLAIM**

The ornamental design for a footwear hanger, as shown and described.

DESCRIPTION

FIG. 1 is a top, front, right perspective view of a footwear hanger showing my new design;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof; and,

FIG. 8 is a bottom, rear, left perspective view thereof.

The broken lines depicting the remainder of the footwear hanger show features that form no part of the claimed design.

1 Claim, 8 Drawing Sheets(56)
